INVENTOR
Paul C. Smalley
BY
Fred C. Fischer
ATTORNEY.

UNITED STATES PATENT OFFICE.

PAUL C. SMALLEY, OF NEWARK, NEW JERSEY.

FLASH-LIGHT DEVICE.

1,346,138.

Specification of Letters Patent. Patented July 13, 1920.

Application filed March 29, 1919. Serial No. 286,186.

To all whom it may concern:

Be it known that I, PAUL C. SMALLEY, a citizen of the United States, residing in the city of Newark, in the county of Essex and State of New Jersey, have invented certain new and useful Improvements in Flash-Light Devices, of which the following is a full, clear, and exact description, such as will enable others skilled in the art to 10 which it pertains to make, construct, and use the same, reference being had to the accompanying drawings, and to numerals of reference marked thereon, forming a part of this specification.

15 My invention relates to search lights or flash lights, and the principal object of the invention is to provide a lens made of glass or other transparent material of peculiar construction, the employment of which will effectively insulate the reflector from the 20 casing without the use of any other insulating means thereby preventing the short-circuiting of the battery.

The employment of my improved lens, 25 also enables me to dispense with the usual screw threaded annular lens retaining member which has screw threaded engagement with the end of the metallic tubular casing containing the cylindrical batteries by 30 means of which the lens is commonly fastened in said annular member and to said casing, thereby reducing the actual number of parts comprising an operative device to an irreducible minimum.

35 With search lights or flash lights of the construction hitherto used, the amount of battery power which can be obtained, is necessarily not great, and it quite frequently happens when devices of this character are 40 employed for work about machinery, etc., and the device is not in use, it is often placed in a tool box or in association with metal tools, where frequently the tools will complete the connection, or such connection will 45 be completed by the metallic parts of the machine, and the energy of the battery expended uselessly, by causing the lamp to burn for hours without the knowledge of the operator and to no useful purpose. With 50 the construction of the lens of the present invention, this is absolutely impossible.

With this end in view, my invention consists in certain novelties of construction and arrangements of parts and is productive of 55 a device exceedingly simple and effective in

construction, comparatively inexpensive in cost and durable in use.

While the preferred forms of my invention are illustrated in the accompanying drawings, yet it is to be understood, that 60 minor changes may be made without departing from the scope thereof.

In the accompanying drawings,

Figure 1 represents a cross section through an embodiment of my invention, 65 illustrating the batteries and lamp in elevation.

Fig. 2 represents a fragmentary cross section of a modified form of my invention.

Fig. 3 represents a fragmentary side elevation of another modified form of my invention, and

Fig. 4 represents a transverse cross section taken on line $x-x$, Fig. 3, looking in the direction indicated by the arrow. 75

Similar characters of reference are employed in all of the above described views to indicate corresponding parts.

Referring now to the said drawings, the reference character 1 indicates a metallic 80 tubular casing containing the cylindrical batteries 2, though of course this casing may be of any convenient form, or other suitable material. 3 represents a screw threaded closure, having screw-threaded engagement 85 with the bottom of the casing 1, wherein a coiled spring 4 is seated for contacting with the zinc electrode of one of the batteries.

The top of the casing 1 is preferably screw threaded to receive the screw threaded portion of the lens 5 by means of which the lens may be fastened in the casing 1. The reflector 6 is provided with the usual central opening into which the lamp socket 7 of the lamp 8 is mounted by any suitable means. 90 The base part 9 of the lamp forms one of the poles, the other pole being shown at 10. 95

When mounted in the casing, one pole of the battery is connected to the casing through the spring 4, as described, and the other pole 11 of the battery is connected directly to the terminal 10 of the lamp, leaving the circuit between the reflector 6 and the casing 1 open.

Suitable means are provided for closing 105 this gap in the circuit when it is desired to operate the lamp, and said means here shown consist of a movable member 12, which engages the casing through contact therewith, and which is slidable in said cas- 110

ing to engage the reflector 6, as clearly indicated in Fig. 2 of the drawings. The end 13 of the movable member 12 is turned up to form a sliding contact with the reflector, 5 so as to insure a bright surface, due to the rubbing of the end 13 over the reflector 6, and thereby a good contact.

Suitable means for operating the member 12 are provided, which consists of a 10 sliding finger piece 14 connected to said member 12 and secured to the casing 1 as is well known.

In order to insulate one terminal of the lamp from the other, and to insulate the reflector 6 from the casing 1, I preferably provide the lens 5 with an annular recess 15 upon its inner face, as clearly indicated in the drawings and fully described and claimed in Patent 1,210,225 granted to me on December 26, 1916, this annular recess being 20 designed to receive the circumferential edge of the reflector 6, thus providing means formed in the lens to prevent the reflector from touching the casing, thereby positively insulating the lamp and battery terminals one 25 from the other, until it is desired to complete the circuit therethrough.

In this manner the edge of the reflector is effectively insulated from the casing and 30 the current is prevented from shunting through the reflector without the use of any other insulating means thereby positively preventing the short-circuiting of the battery.

35 As heretofore stated, by providing the inner or outer peripheral surfaces 16 and 17 of the lens 5 with screw threads corresponding with the screw threaded end of the casing 1, I am thereby enabled to fasten the lens to said casing without employing the usual screw threaded annular lens retaining member, thereby reducing the actual number of parts and the actual cost of manufacture to a minimum.

40 45 I have also found that the construction shown in Figs. 3 and 4 of the drawings is very effective for securing the lens 5 to the casing 1, which consists in providing the circumferential outer surface of the lens

with diametrically oppositely arranged protuberances 18 which may form an integral part of the lens, or otherwise secured thereto, and which have holding or locking engagement with correspondingly arranged slots or recesses 19 formed in the end of the 55 casing 1, or, vice versa, by providing the casing with protuberances and the lens with recesses.

Experience has demonstrated that the organization above described is a highly efficient one, and while I have shown the preferred embodiment of my present invention, I do not wish to be limited to the exact details of construction shown and described, as obvious modifications thereof, not involving the exercise of invention, may be made by any skilled mechanic, and such departure from what is herein set forth, I consider within the scope and terms of my claims.

Having thus described my invention, what 70 I claim as new and desire to secure by Letters Patent is:—

1. In a flash light device of the class described, the combination of a casing, batteries and a lamp therein, a contact device for establishing electrical connections between said batteries and said lamp, a lens provided with integral holding means for securing it to said casing and means on the lens for positioning a reflector circumferentially free 75 within said casing and insulating the reflector from said casing.

2. In a flash light device of the class described, the combination of a casing, batteries and a lamp therein, a contact device 80 for establishing electrical connections between said batteries and said lamp, a recessed lens for positioning a reflector circumferentially free within said casing provided with a screw threaded portion for securing it to the casing and insulating the reflector from said casing.

This specification signed and witnessed this 25th day of March, 1919.

PAUL C. SMALLEY.
